Specification for Design.

Patented Oct. 11, 1921.

Application filed August 21, 1920. Serial No. 405,207. Term of patent 3½ years.

To all whom it may concern:

Be it known that I, GREEN J. WELDON, a citizen of the United States, residing at Anniston, in the county of Calhoun and State of Alabama, have invented a new, original, and ornamental Design for Vehicle-Bodies, of which the following is a specification, reference being had to the accompanying drawing, forming a part thereof.

Figure 1 is a perspective view showing my new design,

Fig. 2 is a top plan view thereof, and,

Fig. 3 is a bottom plan view of a vehicle body showing my design.

I claim:

The ornamental design for a vehicle body, as shown.

GREEN J. WELDON.
